DESIGN FOR A DISPENSER FOR A STACK OF SHEETS

Frank L. Broeren, Neenah, and Archie S. Krueger, Green Bay, Wis., assignors to Marathon Paper Mills Company, Rothschild, Wis., a corporation of Wisconsin

Application December 16, 1940, Serial No. 97,368

Term of patent 14 years

To all whom it may concern:

Be it known that Frank L. Broeren and Archie S. Krueger, citizens of the United States, residing respectively at Neenah, Winnebago County, and Green Bay, Brown County, in the State of Wisconsin, have invented a new, original, and ornamental Design for a Dispenser for a Stack of Sheets, of which the following is a specification, reference being had to the accompanying drawing, forming a part thereof.

We claim:

The ornamental design for a dispenser for a stack of sheets, as shown.

FRANK L. BROEREN.
ARCHIE S. KRUEGER.
